UNITED STATES PATENT OFFICE

JOHN C. CROMWELL, OF ALLIANCE, OHIO, ASSIGNOR TO THE STEEL SANITARY COMPANY, OF ALLIANCE, OHIO, A CORPORATION OF OHIO

APPARATUS FOR ENAMELING ARTICLES

Application filed June 13, 1928. Serial No. 284,964.

The present invention relates broadly to the art of material treatment and handling apparatus therefor, and more particularly to an improved apparatus specially adapted for 5 the treatment and enameling of articles.

In the accompanying drawings there is shown somewhat diagrammatically, for purposes of illustration only and not by way of limitation, a preferred embodiment of the 10 present invention.

In the drawings:—

Figure 1 is a diagrammatic plan view of one form of apparatus and handling equipment in accordance with the present invention; 15

Figure 2 is a transverse sectional view, on an enlarged scale, on the line II—II of Figure 1;

Figure 3 is a transverse sectional view, on 20 an enlarged scale, on the line III—III of Figure 1;

Figure 4 is an end elevational view of one form of article adapted to be handled in accordance with the present invention; and

25 Figure 5 is a longitudinal sectional view through the article of Figure 3 in supported position, certain of the parts being in elevation.

The present invention is centered around 30 an improved furnace and conveyor for effecting the movement of articles to be enameled therethrough, and contemplates the provision of auxiliary equipment cooperating therewith facilitating the preparatory operations 35 and the bringing of the articles in proper condition into position to be passed through the furnace.

In the drawings there is illustrated an 40 enameling furnace comprising preheating and drying chambers 2 and 2', and an intermediate burning chamber 3.

As illustrated in Figure 2 of the drawings, 45 the burning chamber comprises an enclosing wall 4, cooperating with partitions 5, dividing the burning chamber into individual burning chambers 6, 7 and 8. The preheating or drying chambers are located at the ends of the burning chamber, and are preferably constructed as indicated in Figure 3, 50 so that each drying or preheating chamber is

common, with respect to the travel of articles, to all of the individual burning chambers 6, 7 and 8.

Cooperating with all of the chambers and adapted to cooperate therewith to effect the movement of a given article successively through the different chambers, is a conveyor 9, herein illustrated as of an overhead chain type, traveling on angles 10, constituting a track-way therefor. The conveyor is adapted to travel in the direction indicated by the arrows in Figure 1, whereby an article is carried first through one of the drying and preheating chambers into the burning chamber 6, and thence into the drying or preheating chamber 2'. 55 60 65

During the travel of an article through the chamber 6, it is subjected to the highest temperature conditions prevailing in the installation for burning the ground coat onto the 70 same. The continued travel of the conveyor carries the article with its burnt on ground coat into a spraying booth 11, in which the second coat of enamel, either white or colored, is applied to the article. Thereafter, the 75 article so treated is carried through the chamber 2' into the burning chamber 7, wherein it is subjected to a temperature slightly lower than the temperature in the chamber 6, to effect the desired burning of the second coating 80 of the enamel. It will be apparent that during the travel of articles having the second coat thereon through the chamber 2', they are preheated by the articles previously heated in the chamber 6. The articles leaving the 85 chamber 7 in turn give up their heat to incoming articles passing to the chamber 6, and thereby effect preheating thereof.

The articles having the second coat burnt thereon then pass through a spraying booth 90 12, in which they have the third or final coat of enamel applied thereto. The articles thus coated are carried by the conveyor 9 into and through the drying and preheating chamber 2, wherein they are preheated by the articles 95 leaving the chamber 7 before they enter the burning chamber 8. In this chamber they are subjected to a temperature preferably lower than the temperature in the chamber 7. They then pass into the chamber 2' wherein they 100

give up their heat to articles on the conveyor entering the burning chamber 7, and are in turn cooled by this loss of heat.

At this relatively lower temperature, they 5 pass from the chamber 2' to a position adjacent a storing, shipping or handling zone 13, in which they are removed from the conveyor for subsequent disposition.

From the foregoing, it will be apparent 10 that I provide a conveyor means common to three burning chambers, all operating at different temperatures, and common to two pre-heating or drying chambers into and through which the articles must pass both before and 15 after each burning operation, in such manner as to effect a desirable heat interchange there- between with a consequent conservation of the heat of previously burnt articles. Each drying or preheating chamber is in turn com- 20 mon to all of the burning chambers, the burning chambers being arranged in laterally offset relationship, preferably side by side, thereby providing approximately parallel paths of travel therethrough.

25 Each of the burning chambers is preferably provided with heating means in the form of one or more electric heating units 14, by means of which exactly the desired burning temperatures are maintained in the different 30 zones. As before pointed out, the temperature conditions are preferably so controlled that the temperature in the chamber 6 is higher than the temperature in the chamber 7, the temperature in the chamber 7 being in 35 turn higher than the temperature in the chamber 8, so that during the burning of suc- cessive coatings, the articles are subjected to progressively lower temperature conditions, thereby precluding the possibility during sub- 40 sequent burning operations of fusing the previously applied coatings.

In order to effect a further conservation in heat, I preferably surround all of the burning chambers with a chamber 15, adapted to 45 be heated by a relatively inexpensive fuel, such as gas, oil, or coal, such fuels being ef- fective for maintaining the outer walls of the burning chambers at any desired temper- 50 ature equal to or below the temperature in the burning chamber 8. Since the radiation of heat is directly proportional to the square of the temperature difference through the walls, by maintaining a relatively high temper- 55 ature outside of the walls of the burning cham- bers by the use of a relatively inexpensive fuel, the consumption of electric current is reduced to a minimum. In actual practice only about five per cent. (5%) of the total heat is supplied by the units 14, although this 60 percentage may be varied as found desirable for the most satisfactory and economic opera- tion of the installation.

The conveyors are preferably of such con- struction that the loss of heat from the heat- 65 ing furnace is reduced to a minimum and at

the same time the different parts of the conveying mechanism are maintained at different temperatures, thereby permitting the main- tenance of the desired lubrication for the car- 70 rying or supporting portions thereof. Such a condition may be obtained by the use of a mechanism of the general character disclosed in the patent to Beasley and MacDougall, No. 1,603,015, of October 12, 1926. In accordance 75 with such patent, special sealing means 16 is provided for the supporting hooks 17, mounted on the conveyor and projecting into the furnace, and a separate hood 18 for the carrying rollers 19, both of the hoods co- 80 operating with a suitable sealing material 20, 85 of sand or the like.

The hood 18 is adapted to have a cooling medium such as air under pressure supplied thereto through a conduit 21 for keeping the tracks and rollers cool. In case of any pres- 85 sure differential between the cooling medium and the furnace, the difference will be in favor of the cooling medium whereby in case of leakage, the leakage will be from the hood into the furnace, rather than from the fur- 90 nace outwardly.

In Figures 4 and 5 I have shown by way of illustration only, one form of article A adapted to be handled in accordance with the present invention. Such an article may com- 95 prise a bath tub of any desired construction herein illustrated as having end braces 22, formed with trunnion openings 23, adapted to receive the trunnions or hooks 24, on the supporting hooks 17. In this manner a tub 100 is so supported that it may be turned about its longitudinal axis during the spraying operations to thereby facilitate the uniform ap- 105 plication of the coatings thereto.

It will be apparent that the utility of the 105 invention is not limited with respect to the character of the articles being treated, the in- vention being equally applicable to either larger or smaller articles.

Adjacent the chamber 2 there may be pro- 110 vided a dipping tank 25, with which cooper- ates a conveyor 26, in such manner as to per- mit the dipping of the articles preparatory to their passage into the furnace. If desired, the dipped articles may be subjected to a pre- 115 drying operation in the drying chamber 27, through which the conveyor 26 also passes.

This conveyor is preferably so mounted as to pass at some point in a position adjacent the conveyor 9, whereby previously dipped and dried articles may be transferred from one conveyor to the other in order to permit treatment of the character referred to. Co- 120 operating with the conveyor 26 is a pair of conveyors 28, adapted to travel in the direc- 125 tion indicated by the arrows for receiving ar- ticles from carrying means 29 and passing the same through annealing chambers 30 and sand blasting rooms 31 to prepare them, where such preliminary operations are de-

sirable, for application of the ground coat by dipping.

In order to provide for the continuous use of the furnace in cases where it is not desired, 5 for any reason, to treat articles delivered or provided by the conveyor 26, I may provide a conveyor 32, cooperating with a dipping tank 33 and a drying chamber 34. The conveyor 32 at some point preferably travels in 10 a path adjacent a storage chamber 35, in which articles of any desired character may be stored preparatory to enameling. Such articles, for example, may be of the type adapted to be specially treated in accordance with 15 any of the well-known pickling processes.

The present invention in providing for the continuous passage of an article through three different burning zones without the necessity of any removal thereof from the conveyor 20 enables the cost of the enameling operations to be materially reduced, and also increases materially the output of a given installation with a minimum amount of labor.

The elimination of hand labor heretofore 25 required for the removal of articles from securing of articles to the conveyor, particularly during the spraying operations, has resulted in minimizing the number of seconds.

It will be understood by those skilled in the 30 art that changes in the construction and arrangement herein illustrated, as well as in the nature of the articles handled, may be made without departing either from the spirit of the present invention or the scope 35 of my broader claims.

I claim:—

1. A heat treating furnace, comprising 40 three heat treating chambers in lateral offset relationship, and means common to all of said chambers and extending through the roof portions thereof for carrying an article successively therethrough.

2. A heat treating furnace, comprising 45 three heat treating chambers in laterally offset relationship, temperature maintaining means for each of said chambers, in means common to all of said chambers for carrying an article successively therethrough.

3. An enameling furnace, comprising 50 three burning chambers in side by side relationship, means common to all of said chambers for carrying an article successively therethrough, and treating means cooperating with said common means.

55 4. An enameling furnace, comprising three burning chambers in side by side relationship, means common to all of said chambers for carrying an article successively therethrough, and means in the chambers 60 for maintaining progressively lower temperatures in the successive chambers.

5. An enameling furnace comprising a plurality of burning chambers, electric units for maintaining said burning chambers at 65 the desired temperatures, and a heating

chamber enclosing said burning chambers.

6. An enameling furnace, comprising three burning chambers in side by side relationship means for maintaining different temperatures in the different chambers a drying 70 chamber common to all of said burning chambers, and means common to said burning chambers and said drying chamber for carrying an article therethrough.

7. A heating furnace comprising a plurality of high temperature chambers in laterally offset relationship, means for maintaining different temperatures therein, and a plurality of drying chambers each common to all of said high temperature chambers. 75

8. A heating furnace comprising a plurality of high temperature chambers in laterally offset relationship, means for maintaining different temperatures therein, a plurality of drying chambers each common to all of said high temperature chambers, and means common to all chambers for conveying articles therethrough. 80

9. In an enameling apparatus, a furnace, means for delivering dipped articles to a position adjacent the furnace, a plurality of burning chambers in said furnace, and conveying means for receiving a dipped article and supporting the same during successive movement through all of said burning chambers. 90

10. In an enameling apparatus, a furnace comprising a plurality of burning chambers, a conveyor common to all of said burning chambers, and a plurality of independent 100 conveyors for delivering different articles to a position adjacent said first named conveyor.

11. In an enameling apparatus, a furnace comprising a plurality of burning chambers, a conveyor common to all of said burning chambers, a plurality of independent conveyors for delivering different articles to a position adjacent said first named conveyor, and drying means cooperating with each of 105 said last mentioned conveyors.

12. A heating furnace comprising a plurality of high temperature chambers in laterally offset relationship, means for maintaining different temperatures therein, a 110 plurality of drying chambers, each common to all of said high temperature chambers, and means for conveying articles through all of said chambers.

13. A heating furnace comprising a plurality of high temperature chambers in laterally offset relationship, means for maintaining different temperatures in the respective chambers, a drying chamber common to all of said high temperature chambers, and means for conveying articles through all of 115 said chambers.

In testimony whereof I have hereunto set my hand.

JOHN C. CROMWELL. 120
